The ornamental design for a sample cup, as shown and described.

DESCRIPTION

FIG. 1 a perspective view of a sample cup illustrating our new design;

FIG. 2 is a front view thereof, the back view being a mirror image of FIG. 2;

FIG. 3 is a top plan view thereof;

FIG. 4 is a bottom plan view thereof;

FIG. 5 is a front view of a sample cup of FIG. 1, fitting on a primary tube of a first diameter, the back view being a mirror image of FIG. 5; and,

FIG. 6 is a front view of a sample cup of FIG. 1, fitting on another primary tube of a second diameter, the back view being a mirror image of FIG. 6.

The broken lines in FIG. 3 are included for the purpose of illustrating a portion of the sample cup that forms no part of the claimed design. The broken lines showing the tube in FIGS. 5 and 6 represent the environment. None of the broken lines form a part of the claimed design.
